(57) **CLAIM**

The ornamental design for furniture for a commercial aircraft passenger cabin, as shown and described.

DESCRIPTION

FIG. 1 is a rear-left side perspective view of furniture for a commercial aircraft passenger cabin according to my design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a front-right side perspective view of furniture of FIG. 1 shown with commercial aircraft passenger cabin ottoman, seat and partition; and,

FIG. 7 is a top plan view of furniture, ottoman, seat and partition shown in FIG. 6. A second embodiment of the furniture for a commercial aircraft passenger cabin is a mirror image of the design shown in FIGS. 1–7.

No bottom plan and front elevation views are included as no features of the claimed design are visible therein.

Throughout the Figures, the broken lines showing environment or structure are for illustrative purposes only and form no part of the claimed design.
